UNITED STATES PATENT OFFICE.

OTTO GOLDMAN, OF SAN FRANCISCO, CALIFORNIA.

EXHAUST-MUFFLER.

No. 830,660.

Specification of Letters Patent.

Patented Sept. 11, 1906.

Application filed June 8, 1905. Serial No. 264,267.

To all whom it may concern:

Be it known that I, OTTO GOLDMAN, a citizen of the United States, residing at San Francisco, in the county of San Francisco and State of California, have invented certain new and useful Improvements in Exhaust-Mufflers, of which the following is a specification.

My invention relates to improvements in exhaust-mufflers.

The object of my invention is to provide a muffler for explosive-engines which is simple in construction and reduces the sound of the discharge so as to be almost inaudible without throttling such discharge.

My invention consists in the novel combination and arrangement of parts shown in the accompanying drawings, described in the following specification, and claimed in the appended claims.

In my device the deadening of the sound of the exhaust is caused by such an arrangement and combination of parts and apertures as to delay the different parts of the discharge, by making such parts travel along different lengths of free path, thus causing no back pressure.

Referring to the figures designated on the accompanying drawings, Figure 1 represents a longitudinal section of my device. Fig. 2 is a plan view of the same, and Fig. 3 is a transverse section on line X X of Fig. 1. Fig. 4 shows a sectional view of a modification of the device wherein the casing 1 is omitted and Fig. 5 shows a plan view of said modified device.

In the said figures, 1 represents a suitable cylindrical casing having an inlet 2 and an outlet 3 and having an intermediate tapering cylindrical case 8 and an inner tapering tube 4. The tube 4 contains apertures, such as shown at 5. The tube 4 has supports 9, contacting with the interior of the case 8.

The exhaust enters through the inlet 2 into the tapering tube 4 and escaping by means of the holes 5 into the space 6 between such tube 4 and case 8 partly ascends through the opening 7, whereupon it contacts with the interior of the wall above the casing 1 and is there repelled downward through the chamber 10, formed by the wall of said casing 1 and case 8, to and through the outlet 3. The arrows in Fig. 1 illustrate the path of the discharge from its entrance through inlet 1 to its escape through inlet 3, and by the breaking up of the full discharge as it enters

through inlet 2 into different parts, escaping through the respective apertures 5 at varying times and from thence as described, the sound of such discharge is effectually muf- 6c fied, the discharge partly descending at the base of the tapering tube, as well as ascending, as hereinbefore mentioned. The tapering form of the case and tube tends to equalize the exit of the different parts of the dis- 6: charge.

Although I have shown the parts inclosed by casing 1 as tapering and having certain apertures, which is the preferable arrangement of such parts and apertures, the form of 7c such parts and the number of apertures may be somewhat modified without departing from the spirit of my invention.

The discharge escaping gradually by the arrangement of openings, as shown in said 75 modification illustrated in Figs. 4 and 5, accomplishes the muffling of the sound, approximating the result attained by the use of the device shown in Fig. 1.

It is understood that while I have illus- 80 trated and described the preferred arrangement of my invention I reserve the right to make all changes which properly fall within its spirit and scope.

Having thus described my invention, what 85 I claim as new, and desire to secure by Letters Patent, is—

1. In an exhaust-muffler the combination of a casing having at one end thereof a neck constituting an inlet, a tapered tube coincident with said neck having a plurality of apertures, an intermediate tapered case surrounding said tube, out of contact with said tube and casing longitudinally and having end openings, a neck constituting an outlet 90 at the opposite end of said case, substantially as described.

2. In an exhaust-muffler the combination of a casing having an inlet and a discharge opening, a tube in connection with said inlet having an apertured base and side openings and an intermediate case, secured to said base and having apertures, between said tube and the inner wall of said casing, and permitting passages between them, substan- 105 tially as described.

3. In an exhaust-muffler the combination of a casing having an inlet and a discharge opening, a tube in connection with said inlet having an apertured base and side openings, 110 an intermediate case, secured to said base and having apertures, between said tube and

UNITED STATES PATENT OFFICE.

LOUIS STANISLAS ROLLAND, OF BRUSSELS, BELGIUM.

MACHINE FOR ELECTRICALLY WELDING.

No. 830,674.

Specification of Letters Patent.

Patented Sept. 11, 1906.

Application filed September 28, 1905. Serial No. 280,470.

To all whom it may concern:

Be it known that I, LOUIS STANISLAS ROLLAND, a citizen of the Republic of France, residing at Brussels, Belgium, have invented 5 new and useful Improvements in Machines for Electrically Welding, of which the following is a specification.

This invention relates to a machine for electrically welding metal wires, cables, hoop-irons, and generally metal bars of all sections. 10 The machine is also provided with stamping mechanism for removing the bur or the like which results from the welding, so that when the welded parts are removed from the machine the joint is perfectly invisible. 15

The machine is represented in the annexed drawings, in which—

Figure 1 is a plan view thereof; Fig. 2, a front view; Fig. 2^a, a corresponding perspective view of a fragment; Fig. 3, a cross-section on the line 3-3 of Fig. 2; Fig. 4, a plan view of part of the machine with the table removed; Fig. 5, a section on the line 5-5 of Fig. 1; Fig. 6, an elevation of a pair of clip-ping-pincers, and Fig. 7 a plan view of Fig. 6.

The machine comprises a table 10, carrying all the mechanism and adapted to be supported by feet. At the front of this table are mounted two bronze cages 11 and 12, the 20 cage 11 being fixed to the table by bolts and the cage 12 being freely movable in horizontal guides 13, fixed to the table. The work-holders 14 and 15 are formed by blocks of red copper fixed in the cages with insulating plates of vulcanized fiber interposed. To 25 the front of these holders are fixed parts or frames 16 and 17, the upper surfaces of which are provided with recess 18 of the profile and section of the bars to be welded, said frames 30 being opposite each other. These frames can be exchanged according to the shape of the bars to be welded. Below the work-holders are two bronze sockets 81, connected to the terminals of a transformer which supplies current to the machine. 45

The cage 12 is provided with a bridge 19, engaged by a lever 20, pivoted to a fixed axle or pin 21. On the table 10 is fixed a support or bracket 22, through which passes a screw 50 23, serving as an abutment for the tail of the cage. On the other side—that is to say, on the left—the movement of the cage is limited by a finger which abuts against the fixed iron 14.

To the aforesaid lever 20 is attached one 55 end of a spring 25 the other end of which is attached to a pin 26, fixed to the table 10. Near the free end of this lever is fulcrumed a handle 83, pivoted to a connecting-rod 27, connected at its other end with a bell-crank 60 lever 28, pivoted to a fixed support 29. At its free end this lever 28 has a regulating-screw 30, passing therethrough, adapted to abut against the end of a shaft 31, adapted to move longitudinally in bearings 32, secured to the table 10. Near its right-hand end the shaft 31 is provided with a collar 33. Between this collar and the adjacent bearing 32 is compressed a helical spring 34, coiled around the shaft and tending to move the 70 latter toward the right. Adjacent the left-hand end of the shaft 31 a toothed or worm wheel 35 is fixed thereto, meshing with a worm 36, mounted on the shaft of an electro-motor. This wheel 35 is interiorly cut in the 75 form of a hollow cone, with which a cone 37, rigidly mounted on the shaft 31, is adapted to engage by friction. To the shaft 31 there is also fixed a gear-wheel 38, meshing with a gear-wheel 39, mounted on the shaft 40, 80 which is rotatable below the table 10 in bearings 41, secured to the latter. To the shafts 31 and 40 are fixed cams 42 and 43, respectively. The cam 42 acts on a projection 44 of a lever 45, the pivot 46 of which rests in or 85 on a support 47, fixed to the table 10. The cam 43 acts on a lever 48, arranged opposite to the lever 45 and below the table 10, the fulcrum 49 of said lever 48 being carried by a bracket or hanger 50, fixed below the table 90 10, and said two levers 45 and 48 are connected by a spring 51, tending to pull them toward each other. The lever 45 carries the rod 52 of the carrier 53 of an upper matrix 54. The lower matrix 55, having the same 95 vertical axis as the former, is secured in a carrier 56, the lower end of which bears against a regulating-screw 80, passing through one end of the lever 48, Fig. 3. The carrier 56 has a shoulder on which bears a 100 helical spring 57, tending to force said carrier downward. This carrier moves with slight friction in a guide-socket 58, secured to the under surface of the table 10.

Near the front of the machine in holes 105 formed for that purpose in the work-holders 14 and 15 two vertical insulated rods 59 and 60 are adapted to slide, said rods being pro-
